FLUOROSCOPIC VIEWING UNIT

Donald O. North, Menlo Park, Calif.

Application January 5, 1955, Serial No. 33,847

Term of patent 7 years

(Cl. D26—5)

Fig. 1 is a perspective view of a fluoroscopic viewing unit embodying my new design;

Fig. 2 is a reduced side elevational view thereof, the other side being the same; and

Fig. 3 is a reduced front elevational view thereof.

The back and side not shown are substantially plain.

I claim:

The ornamental design for a fluoroscopic viewing unit, as shown and described.
